"INDIA" TEA SPOON.

UNITED STATES PATENT OFFICE.

HIRAM W. HAYDEN, OF WATERBURY, CONNECTICUT, ASSIGNOR TO HOLMES,
BOOTH & HAYDENS, OF SAME PLACE.

DESIGN FOR A FORK AND SPOON.

SPECIFICATION forming part of Design No. 12,553, dated November 1, 1881.

Application filed September 19, 1881. Term of patent 14 years.

To all whom it may concern:

Be it known that I, HIRAM W. HAYDEN, of Waterbury, county of New Haven, in the State of Connecticut, have invented or produced a new and ornamental Design for Spoons and Forks, and the following is a description of the same.

This design relates to the ornaments upon the front and back of the handle of a fork or spoon; and it consists of raised bands, figures, and ornaments upon a smooth or polished background, and said design is known as the "India" pattern.

The accompanying drawing shows both the front and back of a spoon of my new design.

The front of the spoon or fork handle is crossed diagonally by the bands *a a' b b' c c'*, and the spaces between these bands are occupied by "palm" or "shawl-pattern" figures ornamented with leaflet centers and diamond lines on the border. There are stems and leaves between these figures. The corner *d* is plain. The space or panel *e* is ornamented with stems and fruit. The panels *f* and *g* are ornamented with stems and spreading leaves. The bands *h h'* cross the back diagonally, and the band *i* is segmental at the end of the handle, and these bands have ornamental curved figures, as shown, with dots and leaves between. The panel *k* is ornamented with stems, leaves, and flowers, as shown, and the panel *l* with stems, leaves, and heads of grain. The ornamental bands, arched panels, and figures at *m* encircle

the handle of the spoon or fork and form a base to the design. 35

I claim as my invention—

1. The design of the shape and configuration of the bands *a a' b b' c c'*, and the palm or shawl-pattern figures, and stems and leaves between them, substantially as shown and described. 40

2. The design of the shape and configuration of the bands *a a' b b' c c'*, and palm or shawl-pattern figures, and the stem and leaflet designs in the panels *e f g*, substantially as shown and described. 45

3. The design of the shape and configuration of the ornamental bands *h h'* and the ornamental segment at *i*, as shown and described.

4. The design of the shape and configuration of the ornamental bands *h h'*, and *i*, the stem, 50 leaf, and flower design in the panel *k*, and the stem, leaf, and grain-head design in the panel *l*, as shown and described.

5. The design of the ornamental bands, arched panels, and figures *m*, substantially as 55 described.

6. The design of the palm-leaf figures and diagonal bands upon the handle of a fork or spoon, substantially as specified.

Signed by me this 15th day of September, 60
A. D. 1881.

H. W. HAYDEN.
